(57) **CLAIM**

The ornamental design for a buoyant board as shown and described.

DESCRIPTION

FIG. 1 is a perspective view taken from a top, front, right side of a buoyant board according to my design;

FIG. 2 is a perspective view taken from a top, front, left side thereof;

FIG. 3 is a perspective view taken from a bottom, rear, left side thereof;

FIG. 4 is a perspective view taken from a bottom, rear, right side thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof;

FIG. 10 is a bottom plan view thereof;

FIG. 11 is a perspective view taken from a top, front, left side of a buoyant board according to another embodiment of my design;

FIG. 12 is a perspective view taken from a top, front, left side thereof;

FIG. 13 is a perspective view taken from a bottom, rear, left side thereof;

FIG. 14 is a perspective view taken from a bottom, rear, right side thereof;

FIG. 15 is a front elevation view thereof;

FIG. 16 is a rear elevation view thereof;

FIG. 17 is a right side elevation view thereof;

FIG. 18 is a left side elevation view thereof;

FIG. 19 is a top plan view thereof; and,

FIG. 20 is a bottom plan view thereof.

The broken line showing of the buoyant board is for the purpose of illustrating portions of the article that forms no part of the claimed design. The dot-dash boundary line illustrates the boundary of the claimed area.

1 Claim, 20 Drawing Sheets
